UNITED STATES PATENT OFFICE

LUTHER D. LOVEKIN, OF WYNNEWOOD, PENNSYLVANIA

EMERGENCY GAS-SHUT-OFF FIRE VALVE

Application filed October 20, 1927. Serial No. 227,322.

My invention relates to an automatic safety cut-off valve for use in gas supply lines and operative in case of fire, either automatically by rise of temperature at the valve or manually, preferably from outside the building.

A purpose of my invention is to provide an inexpensive valve of the type indicated, particularly well adapted to perform the duties intended.

10 A further purpose is to mount a manually-controlled operating plunger in alinement with the stem of a fuse type of automatic cut-off valve. I spring-press the valve toward closure, normally preventing closure by a mechanically weak fusible member under the stem and adapt the cut-off for hand operation by means of the plunger alined with the stem. The plunger closes the valve by rupturing the fusible member and is preferably operated from outside the building by either water pressure or by mechanical means.

25 A further purpose is to relieve any rising pressure inside the gas meter or like device in the gas line ahead of the valve after the operation of the cut-off by permitting leakage after the operation of the cut-off around the outside of the stem of the valve. I normally seal against such leakage with the fusible material. In the event of fire this 30 fusible seal melts away before the temperature has become such as to produce any undue rise in gas pressure within the meter.

35 A further purpose is to support manually controlled means for operating a fuse type of automatic cut-off valve upon a removable cap alined with the valve.

Further purposes will appear in the specification and in the claims.

40 I have elected to show two only of the many different forms of my invention, selecting forms that are efficient and practical in operation and which well illustrate the principles involved.

45 Figure 1 is an elevation, part section, showing one form of my cut-off device inserted in the gas supply line of a building, with means for manually operating the cut-off from outside the building.

50 Figure 2 is an enlarged vertical longitudinal section of structure shown in Figure 1,

the section being taken in the plane of the paper.

Figure 3 is a vertical fragmentary section illustrating a somewhat different form of my invention installed in the gas supply line 55 of a building on the service side of the supply meter, inside of the building, and illustrating means extending outside the building for manually closing the valve from outside the building.

60 Figure 4 is a fragmentary longitudinal sectional elevation to enlarged scale of the valve shown in Figure 3.

Like numerals refer to like parts in all figures.

Describing in illustration, and not in limitation, and referring to the drawings:—

One of the widest applications of my invention should be in protecting dwellings and for this reason it is illustrated in the assembly views 1 and 3 as connected in the gas supply line of a dwelling, the cut-off device 10 being inserted in the gas line 11 on the service side of the supply meter 12.

70 In the event of fire the cut-off may be effected manually from outside the building at 13, by a fireman or other person.

If the manual cut-off is neglected and the fire progresses sufficiently to heat the valve 80 the cut-off becomes automatic.

The valve body 14 is of globe type and has inlet and outlet compartments 15 and 16 with the usual partition 17 of the globe type of valve.

85 The body has transversely alined openings 18, 19 and 20 respectively in the outside wall of one of the compartments through the partition and through the outside wall of the other compartment. A valve seat 21 extends around the opening 19 through the partition. Inlet and outlet connections of the gas line are shown at 11 and 22 respectively.

90 The movable valve member comprises a disc 23 mounted upon an intermediate portion of a stem 24.

95 The lower portion of the stem loosely passes through the opening 20 in the outside wall of the compartment 16 and leakage around the stem is prevented by a closure that comprises a cap member 26 threaded upon an external 100

flange 27 of the body around the opening and a disc heat-sensitive element 28 of material that is mechanically weak at ordinary temperatures and fusible at abnormal temperatures considered dangerously high.

5 The cap is bored axially at 29 below the bottom of the stem with a diameter somewhat larger than that of the stem and the disc heat-sensitive element 28 rests in the cap across the upper end of the bore supporting the bottom of the stem so as to hold the valve open.

10 The valve member 23 is coaxial with its stem and is clamped to place between a shoulder 30 on the lower side and a nut 31 upon the upper side threaded upon an enlarged portion 15 32 of the stem.

The upper end of the valve unit is received in a cap or hollow plug 33 threaded into the body opening 18 and the valve unit may be 20 removed through this opening when the plug is removed.

25 Preferably the valve disc is provided with an upwardly extending annular apron 34 that loosely fits an interior bore 35 of the plug. The disk is spring-pressed toward its seat by a spiral spring 36 compressed between the disc and the interior of the cap.

I mount a plunger 37 upon the cap member alined with the stem of the valve. This 30 plunger is adapted to engage the top of the stem and to close the valve against the resistance of the mechanically weak heat element 28, shearing through the heat element.

In the form shown in Figures 1 and 2 the 35 upper end of the plunger is enlarged to form a piston which operates inside a suitable cylindrical casing 38 and is preferably circumferentially grooved at 39.

The casing 38 is provided with one or 40 more drain holes 40 at the bottom and with a cover 41 to which water pressure connection is made at 42, the pressure connection pipe being provided with a valve 43 that is preferably controlled from outside the building.

45 In Figure 1 the stem 44 of the water valve is extended through the foundation wall 45 of the building. An outside handle or wrench grip 46 being provided that is desirably placed inside a suitable box 47. In 50 Figure 1 this box is cylindrical and is provided with a removable screw cap 48.

Desirably the lower end of the plunger is bored at 49 to receive the upwardly extending end of the stem. This, however, is to a considerable extent a matter of preference.

55 The mechanically weak heat element beneath the bottom of the stem should be sufficiently strong at normal temperatures to support the weight of the movable valve member 60 and in the structure illustrated in Figures 1 and 2 also the weight of the plunger.

If the disc heat sensitive element fails by 65 fusion, the spring 36 snaps the valve shut usually without any immediate change in the position of the plunger.

I have illustrated both in Figure 2 and in Figure 4 an inwardly extending body flange 50 around the lower end of the stem. This inside flange assists somewhat in guiding the stem, but where desired may be 70 omitted.

Obviously either compartment of the valve may be made inlet and the other the outlet and in Figure 2 I have illustrated the inlet as being upon the upper or disc side of the body while in Figure 4 I show the inlet compartment as that upon the lower side, that is upon the side away from the disc valve.

75 The first arrangement is usually preferable in that it permits escape of gas imprisoned in the line ahead of the valve as from the meter, as already explained but the second arrangement has some advantages.

80 With the first arrangement if the disc 28 melts away, letting the valve snap shut, any rise in gas pressure inside the meter is relieved by leakage around the lower end of the stem, a leakage that is normally prevented by the sealing heat element inside the cap 26.

85 Figures 2 and 4 show different forms of plungers carried in alinement with the stem of the valve by the cap or plug member 33 and adapted for manual operation for closing the valve against the resistance of the heat-sensitive element by sharing the heat-sensitive element.

90 In Figure 4 the plunger comprises a rod provided at its lower end with a shoe 51 adapted to engage the top of the stem. The rod extends upwardly through a gland 52 upon the top of the plug and makes operating connection at 53 with a rocker arm 54.

100 The rocker 54 is pivoted at 55 upon an upwardly extending bracket 56 that is preferably an integral portion of the body of the valve and is provided with an operating arm 57 having flexible connection 58 through a conduit 59 to a reel 60 mounted in a box 61 outside the building.

105 Manual operation of the valve is effected by opening the door 62 of the box and winding the handle 63 of the reel sufficiently to shear the heat element by the downward pressure upon the plunger.

110 While I have illustrated the lower compartment in Figure 4 as the inlet compartment, and the upper compartment as the outlet compartment it will be understood that the reverse arrangement will often be more 115 desirable in that it is better adapted to relieve any pressure inside the meter due to heating imprisoned gas, but in certain cases the arrangement shown, that in which the lower compartment is inlet is preferable.

120 In view of my invention and disclosure variations and modifications to meet individual whim or particular need will doubtless become evident to others skilled in the art, to obtain all or part of the benefits of 125

my invention without copying the structure shown and I, therefore, claim all such in so far as they fall within the reasonable spirit and scope of my invention.

It will be noted that the stem 64 of the hydraulic piston 37 carries closure members presenting faces 65 and 66 to engage respectively with seats 67 and 68 at the upper and lower positions of the piston to shut off leakage from the gas supply into the cylinder.

The member having the face 65 can be set against its seat 67 by tightening up the nut 26 so as to maintain gas tightness at this, the most vulnerable part of the system.

Having thus described my invention what I claim as new and desire to secure by Letters Patent is:

1. A cut-off valve adapted for manual operation spring-pressed toward closure and a heat sensitive element normally blocking the spring-pressed member from closure, said element being adapted to be sheared when volitionally closing the valve.

2. A fusible type of automatic cut-off valve having a valve spring-pressed toward closure, normally prevented from closure by a mechanically weak heat element and an opening in the side of the valve body sufficient to pass the valve, in combination with a plug member closing the opening, and means external to the valve supported thereon adapted to rupture said heat element and close the valve.

3. An automatic gas cut-off valve for use in the gas supply line of a building, located in the building, a fusible element restraining closure of the valve, water pressure operated means for rupturing the fusible element and forcing the valve to close and a hand control for the water supply means accessible outside of the building.

4. In a gas cut-off valve adapted to be inserted into a gas supply line, a globe valve body having inlet and outlet compartments and a partition wall therebetween and having transversely aligned openings progressively smaller respectively in the outside wall of one of the compartments, in the partition and in the outside wall of the other compartment, a valve seat around the opening in the partition, a disc inside the compartment having the larger opening and adapted to engage the seat to close the opening in the partition, a stem supporting the disc at an intermediate point and extending through the opening in the partition and the opening in the said other compartment, and a closure of the opening in said other compartment comprising a mechanically weak fusible member normally supporting the end of the stem so as to maintain the disc away from its seat and removable means for holding the fusible member in place, in combination with a cap closing the opening in the outer wall of the first compartment,

partment, spring means within the cap pressing the disc toward closure, a plunger aligned with the stem adapted to force the stem through the fusible member to close the valve and means external to the valve for operating the plunger.

5. In a gas cut-off valve adapted to be inserted into a gas supply line, a globe valve body having inlet and outlet compartments and a partition wall therebetween and having transversely aligned openings progressively smaller, respectively in the outside wall of one of the compartments, in the partition and in the outside wall of the other compartment, a valve seat around the opening in the partition, a disc inside the compartment of the larger opening adapted to engage the seat to close the opening in the partition, a stem supporting the disc at an intermediate point and extending through the opening in the partition and the opening in the said other compartment, and a closure of the opening in said other compartment comprising a mechanically weak fusible member normally supporting the end of the stem so as to maintain the disc away from its seat and removable means for holding the fusible member to place, in combination with a cap closing the opening in the outer wall of the first compartment, spring means aligned with the stem pressing the disc toward closure, plunger means aligned with the stem and adapted to engage the end of the stem and supported by the cap, a cylinder supported by the cap, encasing the plunger and a hand-controlled water pressure connection with the outer end of the cylinder.

6. In a gas cut-off valve adapted to be inserted into a gas supply line of a building, a globe valve body having inlet and outlet compartments and a partition wall therebetween and having transversely aligned openings, respectively in the outside wall of one of the compartments, in the partition and in the outside wall of the other compartment, a valve seat around the opening in the partition, a disc inside the compartment of the larger opening, adapted to engage the seat to close the opening in the partition, a stem supporting the disc at an intermediate point and extending through the opening in the partition and the opening in the said other compartment, and a closure for the opening in said other compartment comprising a mechanically weak fusible member normally supporting the end of the stem so as to maintain the disc away from its seat and removable means for holding the fusible member to place, in combination with a cap closing the opening in the outer wall of the first compartment, spring means aligned with the stem pressing the disc toward closure, plunger means aligned with the stem and adapted to engage the end of the stem and supported by the cap, a cylinder

der supported by the cap encasing the plunger, water-pressure connection with the cylinder at the outer end thereof, a valve in the connection controlling the admission of water to the cylinder and an operating handle thereof outside the building.

7. In a protective device for closing gas valves in case of fire, a gas pipe, a spring-pressed fusible-element-restrained closing valve connected therewith and located inside the house, a power-operated closing device for the valve adapted to shear the fusible element and a device external to the valve extending outside the house for operation of the said closing device.

8. In a protective device for shutting off the gas supply in case of fire, a gas pipe, a valve connected therewith located within the house and having a closing spring, a fusible element restraining the valve from spring closure but permitting closure with greater pressure, an hydraulic cylinder connected to the house water supply, a piston therein adapted to add pressure to the spring pressure to force the valve shut and a control valve for the water connection accessible for operation from the outside of the house.

9. In a device for closing gas valves in case of fire, a gas pipe, a normally open gas valve spring-pressed toward closure and permitting forced closure, a fusible element restraining closure and fluid-operated means for bringing pressure upon the valve additional to the spring pressure to rupture the fusible element and force closure.

10. In a protective device for closing gas valves in case of fire, a gas pipe, a gas valve in the pipe spring-pressed toward closure, a stem connected with the valve, a fusible-element of weak mechanical strength in line with the stem and supporting it against valve closure and means for forcing the valve stem against the fusible-element to overcome its support and to close the valve and means outside the house whereby the first means may be set in motion.

11. In a device for closing gas valves in case of fire, a gas valve normally held open, an hydraulic cylinder connected with a water supply, a piston in the cylinder, a stem from the piston and connections adapted to close the gas valve, closures carried by the piston and stem and adapted to protect from leakage of water into the body of the gas valve, and means for controlling the water supply cooperating with the piston and connections for closing the gas valve.

LUTHER D. LOVEKIN.
